(57) **CLAIM**

The ornamental design for a housing for dock and mixer for media players, as shown and described.

DESCRIPTION

FIG. 1 is a perspective view of a housing for dock and mixer for media players showing our new design;

FIG. 2 is a front elevational view thereof;

FIG. 3 is a rear elevational view thereof;

FIG. 4 is a top view thereof;

FIG. 5 is a bottom view thereof;

FIG. 6 is a left side elevational view thereof; and,

FIG. 7 is a right side elevational view thereof.

The broken line showing of the portable media players, and example layout for buttons, knobs, sliders and jacks are included for the purpose of illustrating environmental structure and forms no part of the claimed design.
